UNITED STATES PATENT OFFICE.

FRANK LANTIERI AND GABRIEL LANTIERI, OF JERSEY CITY, NEW JERSEY.

HAIR-WAVING DEVICE.

Application filed October 21, 1920. Serial No. 418,374.

To all whom it may concern:

Be it known that we, FRANK LANTIERI and GABRIEL LANTIERI, citizens of the United States, residing at Jersey City, in the county 5 of Hudson and State of New Jersey, have invented certain new and useful Improvements in Hair-Waving Devices; and we do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

This invention relates, generally, to improvements in hair-waving machines; and, the present invention has reference, more particularly, to a novel apparatus or machine, primarily, in the form of an electric chandelier which is provided with a plurality of plug-receiving sockets, for attachment to the chandelier of a plurality of electric heaters, which are adjustably disposed and which may be variously arranged upon and about the hair upon the head of a person, so as to be readily used for producing permanent hair-waving. 20

One of the principal objects of the present invention is to provide an electric chandelier of the general character hereinafter more fully set forth with a plurality of plug-receiving sockets, a plurality of hair-waving heaters being each adjustably connected 25 with the chandelier so as to be properly arranged upon and about the hair upon the head of a person, and the several heaters being electrically connected with the usual sockets. 30

A further object of the present invention is to provide in connection with an electric fixture, usually in the form of a chandelier, an adjustably disposed clamping or retaining means, adapted to be clamped or brought 35 into holding engagement with the lead or cable of a hair-waving heater, whereby the latter can be variously suspended in a vertically adjusted relation above the head of a person, and when not in use can be readily

and quickly raised out of the way of the person seated beneath the apparatus. 50

Another object of the present invention is to provide a novel and improved construction of hair-waving heater, the main body of which is larger at its one end than at the opposite end thereof, so that two or more of the heaters can be arranged upon the head of the person in an arc-shaped relation, or where a sufficient number of heaters are used, the said heaters may be placed upon 55 the head so as to form a complete circle, or any arc thereof. 60

Other objects of the present invention not at this time more particularly enumerated will be clearly understood from the following detailed description of the present invention. 65

With the various objects of the present invention in view, the said invention consists, primarily, in the novel hair-waving machine or apparatus hereinafter more fully set forth; and, the said invention consists, furthermore, in the novel arrangements and combinations of the several devices and parts, as well as in the details of the construction of the said parts, all of which will be more fully described in the following specification, and then finally embodied in the clauses of the claims which are appended to and which form an essential part of the 70 said specification. 75

The invention is illustrated in the accompanying drawings, in which:—

Figure 1 is a side elevation of a hair-waving apparatus showing one embodiment 85 of the principles of the present invention, the view representing in connection therewith a pair of hair-waving heaters in suspended relation to the apparatus, and illustrating, furthermore, the angular arrangement of the two heaters, side by side, whereby the heater may be placed in arc-shaped 90 or circular disposition upon the head of the person.

Figure 2 is a bottom view of the apparatus, the heaters with their attaching means being omitted from said view. 95

Figure 3 is a plan view of the apparatus,

with the top-cover of the enclosing shell of the apparatus removed, to illustrate one general arrangement of the interiorly disposed devices of the apparatus.

5 Figures 4 and 5 are elevations of the opposite sides of one of the spring-controlled heater-suspension spools used with the apparatus; Figure 6 is an elevation of the same, with one of the side-members omitted 10 from said view, so as to show the general arrangement of an interiorly disposed spiral spring; and Figure 7 is a horizontal sectional representation of the spool, certain portions of the device, however, being shown in 15 plan.

Similar characters of reference are employed in all of the said above described views, to indicate corresponding parts.

Referring now to the several figures of the 20 drawings, the reference-character 1 indicates a suitable ornamental chandelier, the same comprising a chambered body consisting of a lower shell or member 2, with the surrounding marginal flange-like element 3 of 25 which is suitably connected an upper shell or member 4, the said members 2 and 4 being mounted in fixed position upon a stem or rod 5 in any suitable manner, for suspension of the apparatus from the ceiling, as will be 30 clearly evident. The said chambered body thus provided may be of any suitable size and configuration that may be desired. Circularly spaced about the flat portion 6 of the 35 said lower shell or member 2, are suitable holes or openings in which are disposed suitably formed tubular members, as 7, securely fixed in place by lock-nuts 8 and 9, on opposite sides of the shell, as shown in Figures 1 and 3, each tubular member carrying upon 40 its lower end-portion an electric receiving socket, as 10, of any usual type and construction. Similarly, the annular marginal flange 3 of the said lower shell or member 2 is provided with a pair of suitably disposed 45 openings in which are disposed suitably formed tubular members 11, securely fixed in place by lock-nuts 12 and 13 on opposite sides of the said flange 3, said tubular members carrying upon their other end-portions 50 electric receiving sockets, as 14 and 15, of any usual type and construction, as will be clearly evident from Figures 1, 2 and 3 of the drawings. Leading in from the said socket 14 is an electric cable, as 16-16, 55 which is electrically connected with one of the said sockets 10, and with which the other sockets 10 and the socket 15 are electrically connected by means of the circuit-wires 17-17, as will be evident from an inspection of Figure 3 of the drawings. It 60 will be understood, however, that the arrangement here shown for electrically connecting in circuit the various sockets may be changed without departing from the 65 scope of the present invention, as we are

fully aware, that the several sockets may be otherwise arranged and may be differently connected in electric circuit.

Connected with the socket 15 may be an electric lamp of any suitable construction 70 which may serve as a resistance and also for illuminating purposes.

Adapted to be screwed, or otherwise secured in the several sockets 10, as in one of said sockets as shown in Figure 1 of the 75 drawings, are contact-plugs 18 and electrically connected with each plug 18 is an electric cable 19, which as is shown in the present case may terminate in branch cables 20 and 21, within a suitable fixture 22, 80 the said branch-cables usually extending through the apertures of an adjusting member 122 of any usual form and construction, and each cable being electrically connected with an electric heater, as 23, in which a portion 85 of the hair of a person is adapted to be arranged for permanent hair waving. The said electric heaters may be of any suitable construction, except that the outer shells or bodies of the respective heaters are 90 made at one end with annular enlargements, as 24, which provide spacing heads so that the heaters when placed side by side with their inner ends and the said spacing-heads in contacting relation, as represented in Figure 1 of the drawings, may be angularly arranged with relation to one another, so that any desired number of such heaters may be 95 located in a circle or in an arc forming part of a circle upon the head of the person, to 100 enable the operator to employ a large number of such heaters, when found desirable.

As will be seen from an inspection of Figure 1 of the drawings, the inner end-portions 123 of the bodies of said heaters 23, 105 are squared with relation to the cylindrical bodies of the heaters, each squared end being of substantially the same cross-area of the body, whereby with an arrangement of the heaters, as above stated, they are adapted to 110 contact at both ends, so that a large number of heaters can be arranged circularly in a minimum space upon the head of the person being treated.

That the several heaters may be adjustably suspended with relation to the chandelier and with relation to the head of the person suitable adjusting means or devices may be employed.

One arrangement of such adjusting devices is shown in connection with the drawings filed with this application. One general arrangement of such devices is more particularly represented in Figure 3 of the drawings, and the detail construction of each 120 adjusting device is illustrated more particularly in Figures 4, 5, 6 and 7. As shown, in the present instance, the base 25 of the 125 previously mentioned lower shell or member 2 of the chandelier has a number of circu- 130

larly arranged screw-threaded posts or standards 26 suitably secured in vertical positions by an arrangement of tightening or lock-nuts 27 and 28, with a lock-washer 29 usually arranged upon each post between the nut 28 and the upper surface of the base 25. Upon its upper screw-threaded end-portion, each post 26 is provided with a supporting means, usually in the form of a nut 30, upon which is placed and embracing the shank of the post, the eye or loop-portion 32 of a cotter-pin 31, or other suitably formed spindle, for the purposes to be presently described. Each cotter-pin is rigidly secured in its proper horizontal relation, by the said nut 30 and a nut-lock 33 against an enlargement or head 34 with which the post 26 is provided.

Rotatably disposed upon the split shank 20 of each cotter-pin, and held against displacement from the latter by means of suitably formed collars 35 and 36, the latter having retaining portions 37 forced into depressions 137 in the said split shank-portion 25 of the cotter-pin, as shown in Figure 7 of the drawings, or other suitable fastening means, is a spring-controlled spool, as 38. Each spool, as will be seen more particularly from an inspection of said Figure 7, consists 30 of a pair of side-discs or plates 39 and 40, between the outer edge-portions of which is clamped, or otherwise secured, a cylindrical drum-portion 41, all arranged to provide a hollow or chambered spool or sheave, 35 having an outer peripheral cord-receiving and guiding portion, as 42. Suitably disposed within the chamber 43 thus provided is a spiral spring 44, having its outer end-portion 45 suitably secured to the drum-portion 41, and having its inner end-portion 46 in clamped arrangement between the split shank-portion of the cotter-pin, substantially as shown in Figures 6 and 7 of the drawings, with its free portion 47 arranged about one of the shank-portions of the cotter-pin and secured by means of a rivet 48. To strengthen the said fastened end portion, the parts may be encased in a protecting re-inforcing band 49, which surrounds the cotter-pin and is secured in place by the said rivet 48, substantially as shown in Figure 6 of the drawings.

Normally wound upon the cylindrical drum 41 of each spool or sheave, with its one end inserted through a perforation 50 in the plate or disc 39 and suitably secured, is a coiled tape or cord 51, or other flexible connection, the free end-portion of which is run through a hole or opening 52 in the base 60 of the lower shell 2, said free end-portion of the tape or cord 51 having secured thereto a suitably constructed clamp, as 53, the pivotally connected and spring-actuated grasping jaws of which are adapted to be brought into holding engagement with any

suitable portion of the electric cable 19, in a manner as clearly shown in Figure 1 of the drawings.

From an inspection of said Figure 1 it will be evident, that the suspended heaters, thus carried by the tapes or cords, will counterbalance the action of the spiral springs so that the operator can pull the heaters in a downward direction any degree that may be desired, or he may allow the spring to assume its rewinding action, so that the heaters, when not in use, will be suspended at suitable heights above the person, either before or after application to the hair upon the head.

If desired, the upper shell or member 4 of the chandelier may be provided with suitably disposed posts or standards 54 carrying a ring 55 which is provided with hooks 56, or other means of suspension, over which the coils of the heater can be placed, for suspending the heaters entirely out of the way, when not in use.

From the foregoing description of the present invention, it will be clearly seen that we have devised a simply constructed, as well as an ornate device, in the form of a chandelier, which may be provided with any desired number of adjustable heaters adapted for permanently waving the hair of a person, the heaters being arranged in such a manner, that all may be used at one time, or when desired only part of the heaters may be used.

We are fully aware, that changes may be made in the general arrangements and combinations of the various devices and parts, as well as in the details of the construction of the said parts, without departing from the scope of the present invention as set forth in the foregoing specification, and as defined in the clauses of the claims which are appended to the said specification. Hence, we do not limit our present invention to the exact arrangements and combinations of the various devices and parts as described in the said specification, nor do we confine ourselves to the exact details of the construction of the said parts as illustrated in the accompanying drawings.

We claim:

1. In a device of the kind described, a main chambered casing, a plurality of sockets carried by said casing, a hair-waving heater connected with each socket, and a means of adjustment carried by and enclosed within said casing and co-operating with each heater for lowering or raising the heater.

2. In a device of the kind described, a main chambered casing, a plurality of sockets carried by said casing, a hair-waving heater connected with each socket, and a means of adjustment carried by and enclosed within said casing and co-operating

- with each heater for lowering or raising the heater, each heater having an annular enlargement at one end, so that the heaters may be arranged side by side in an arc-shaped or circular relation. 5
3. In a device of the character described, a chambered casing, a plurality of electric sockets carried by said casing, a hair-waving heater electrically connected by means of a flexible cable with each socket, and a means of adjustment within said casing and co-operating with the flexible cable of a heater for lowering or raising the heater. 10
4. In a device of the character described, a chambered casing, a plurality of electric sockets carried by said casing, a hair-waving heater electrically connected by means of a flexible cable with each socket, and a means of adjustment within said casing and co-operating with the flexible cable of a heater for lowering or raising the heater, each heater having an annular enlargement at one end, so that the heaters may be arranged side by side in an arc-shaped or circular relation. 20
5. In a device of the character described, a chambered casing, a plurality of electric sockets carried by said casing, a hair-waving heater electrically connected by means of a flexible cable with each socket, a series of spring-controlled spools within said casing, a flexible connection wound upon each spool, each flexible connection having its free end-portion extending from said casing, and means connected with the extending free end-portion of each flexible connection for attachment to the flexible cable of a heater for lowering or raising the heater. 30
6. In a device of the character described, a chambered casing, a plurality of electric sockets carried by said casing, a hair-waving heater electrically connected by means of a flexible cable with each socket, a series of spring-controlled spools within said casing, a flexible connection wound upon each spool, each flexible connection having its free end-portion extending from said casing, and means connected with the extending free end-portion of each flexible connection for attachment to the flexible cable of a heater for lowering or raising the heater, each heater having an annular enlargement at one end, so that the heaters may be arranged side by side in an arc-shaped or circular relation. 45
7. In a device of the character described, a chambered casing, a plurality of electric sockets carried by said casing, a hair-waving heater electrically connected by means of a flexible cable with each socket, a series of spring-controlled spools within said casing, a flexible connection wound upon each spool, each flexible connection having its free end-portion extending from said casing, and means connected with the extending free end-portion of each flexible connection for attachment to the flexible cable of a heater for lowering or raising the heater, each heater having an annular enlargement at one end, so that the heaters may be arranged side by side in an arc-shaped or circular relation. 60
8. In a device of the character described, a chambered casing, a plurality of electric sockets carried by said casing, a hair-waving heater electrically connected by means of a flexible cable with each socket, a series of spring-controlled spools within said casing, a flexible connection wound upon each spool, each flexible connection having its free end-portion extending from said casing, and means connected with the extending free end-portion of each flexible connection comprising spring-actuated clamping jaws adapted to be brought into clamping relation with the flexible cable of a heater for lowering and raising the heater. 70
9. In a device of the character described, a chambered casing, a plurality of electric sockets carried by said casing, a hair-waving heater electrically connected by means of a flexible cable with each socket, a series of circularly disposed vertical posts within said casing, a laterally extending spindle carried by each post, a spring-controlled spool rotatably mounted upon each spindle, a flexible connection wound upon each spool, each flexible connection having its free end-portion extending from said casing, and means connected with the extending free end-portion of each flexible connection comprising spring-actuated clamping jaws adapted to be brought into clamping relation with the flexible cable of a heater for lowering and raising the heater. 80
10. In a device of the character described, a chambered casing, a plurality of electric sockets carried by said casing, a hair-waving heater electrically connected by means of a flexible cable with each socket, a series of circularly disposed vertical posts within said casing, a laterally extending spindle carried by each post, a spring-controlled spool rotatably mounted upon each spindle, a flexible connection wound upon each spool, each flexible connection having its free end-portion extending from said casing, and means connected with the extending free end-portion of each flexible connection comprising spring-actuated clamping jaws adapted to be brought into clamping relation with the flexible cable of a heater for lowering and raising the heater. 90
11. In a device of the character described, a main chambered casing, hair-waving heaters flexibly connected with said casing, and

a means of suspension carried by and enclosed within said casing with which said heaters can be brought into suspended relation when not in use.

5 12. In a device of the character described, a main casing, hair-waving heaters flexibly connected with said casing, and a means of suspension carried by said casing with which said heaters can be brought into sus-

10 pended relation when not in use, consisting of posts secured and extending upwardly from said casing, a band carried by said posts, and hooks secured to and carried by said band.

15 13. In a device of the character specified, in combination with a chambered casing and a hair-waving heater electrically connected therewith by means of a flexible cable, of an adjusting device within said casing

20 comprising a post, a spindle extending horizontally from said post, a spring-controlled spool rotatably mounted upon said spindle, and a flexible connection wound upon said spool, said flexible connection having its free end-portion extending from said casing and secured to a portion of said flexible cable.

25 14. In a device of the character specified, in combination with a chambered casing and a hair-waving heater electrically connected therewith by means of a flexible cable, of an adjusting device within said casing comprising a post, a spindle extending horizontally from said post, a spring-controlled

30 spool rotatably mounted upon said spindle, a flexible connection wound upon said spool, said flexible connection having its free end-portion extending from said casing and secured to a portion of said flexible cable, and a clamping device detachably connected with a portion of said flexible cable.

35 15. In a device of the character specified, in combination with a chambered casing and a hair-waving heater electrically connected therewith by means of a flexible cable, of an adjusting device within said casing comprising a post, a split spindle in the form of a cotter-pin having an eye-portion mounted upon said post, means upon said

40 post for securing said eye-portion in a fixed position upon said post, a spring-controlled spool rotatably mounted upon the split-members of said spindle, said split-members being formed with retaining depressions, a retaining collar upon said split-members having portions

45 having portions forced into said retaining depressions so as to secure said collar against movement upon said split-members, and a flexible connection wound upon said spool, said flexible connection having its free end-portion extending from said casing and secured to a portion of said flexible cable.

50 16. In a device of the character specified, in combination with a chambered casing and a hair-waving heater electrically connected

therewith by means of a flexible cable, of an adjusting device within said casing comprising a post, a split spindle in the form of a cotter-pin having an eye-portion mounted upon said post, means upon said post for securing said eye-portion in a fixed position upon said post, a spring-controlled spool rotatably mounted upon the split-members of said spindle, said split-members being formed with retaining depressions, a retaining collar upon said split-members having portions forced into said retaining depressions so as to secure said collar against movement upon said split-members, a flexible connection wound upon said spool, said flexible connection having its free end-portion extending from said casing, and a clamping device detachably connected with a portion of said flexible cable.

55 17. The herein-described adjusting device for a hair-waving heater, comprising a post, a split spindle in the form of a cotter-pin having an eye-portion mounted upon said post, means upon said post for securing said eye-portion in a fixed position upon said post, a spring-controlled spool rotatably mounted upon the split-members of said spindle, said split members being formed with retaining depressions, a retaining collar upon said split-members having portions forced into said retaining depressions so as to secure said collar against movement upon said split-members, and a flexible connection wound upon said spool.

60 18. The herein-described adjusting device for a hair-waving heater, comprising a post, a split spindle in the form of a cotter-pin having an eye-portion mounted upon said post, means upon said post for securing said eye-portion in a fixed position upon said post, a spring-controlled spool rotatably mounted upon the split-members of said spindle, said split-members being formed with retaining depressions, a retaining collar upon said split-members having portions forced into said retaining depressions so as to secure said collar against movement upon said split-members, a flexible connection wound upon said spool, and a clamp attached to the free end-portion of said flexible connection, said clamp comprising a pair of spring-actuated clamping jaws.

65 19. A hair-waving heater comprising a main cylindrical body formed at its outer end with enlarged spacing head, said cylindrical body having a squared end of substantially the same cross-area of said body, all arranged so that the inner end-portion of one body may be brought in contact with the inner end-portion of another body, and that the spacing-head of the one body may be brought in contact with the spacing-head of the other body, and whereby a plurality of such contacting heaters may be arranged side by side in an arc-shaped or circular re-

lation, the central longitudinal axes of the adjacent and angularly arranged heaters, when extended from said squared ends meeting in a single point which is the center of an arc of which the said squared ends are cords, substantially as and for the purposes set forth.

In testimony, that we claim the invention

set forth above we have hereunto set our hands this 18th day of Oct, 1920.
